(57) **CLAIM**

The ornamental design for a gantry control panel, as shown and described.

DESCRIPTION

FIG. 1 is a perspective view of a portion of a medical imaging system incorporating the design of the present invention;

FIG. 2 is a front elevational view of a gantry control panel in accordance with the present invention;

FIG. 3 is a top view of the gantry control panel of FIG. 2; FIG. 4 is a left side view of the gantry control panel of FIG. 2;

FIG. 5 is a right side view of the gantry control panel of FIG. 2;

FIG. 6 is a bottom view of the gantry control panel of FIG. 2;

FIG. 7 is a rear elevational view of the gantry control panel of FIG. 2;

FIG. 8 is a perspective view of a rear portion of a medical imaging system showing an alternate placement of the gantry control panel of FIG. 2;

FIG. 9 is a perspective view of a medical imaging system incorporating an alternate embodiment of the design of the present invention;

FIG. 10 is a perspective view of a rear portion of a medical imaging system showing an alternate embodiment of the design of the present invention; and,

FIG. 11 is a front elevational view of a gantry control panel similar to that shown in FIG. 2 and incorporated into the systems shown in FIGS. 9 and 10.

The broken lines shown in all figures are for illustrative purposes only and form no part of the claimed design.
